UNITED STATES PATENT OFFICE.

ALEXANDER L. RUNYON, OF NEW YORK, N. Y., ASSIGNOR TO THE BRANFORD LOCK-WORKS, OF BRANFORD, CONNECTICUT.

DESIGN FOR KEYS.

Specification forming part of Design No. 7,788, dated October 6, 1874; application filed August 23, 1874.
[Term of Patent 7 years.]

To all whom it may concern:

Be it known that I, ALEXANDER L. RUNYON, of New York, in the county of New York and State of New York, have invented a new Design for Key; and I do hereby declare the following, when taken in connection with the accompanying drawing and the letters of reference marked thereon, to be a full, clear, and exact description of the same, and which said drawings constitutes part of this specification, and represent, in—

Figure 1, a perspective view, and in Fig. 2 a transverse section, through the spindle.

This invention relates to a design for key for door-locks, the peculiar feature of the design being the shape of the spindle between the bit and bow; and it consists in making

that portion of the key square in transverse section, with two opposite angles in vertical line with or in the plane of the bow.

A is the bit, B the bow, of substantially the usual form. The part C of the spindle is square in transverse section, as seen in Fig. 2, two opposite angles in vertical line with the bow.

I claim as my invention—

The design for key, consisting of the square spindle C, with two opposite angles in plane of the bow, as shown and described.

A. L. RUNYON.
